UNITED STATES PATENT OFFICE.

FREDERICK W. TOLLEY, OF HUDSON, NEW YORK, ASSIGNOR OF ONE-HALF
TO EMANUEL VOLK, OF SAME PLACE.

BUTTER AND LARD CUTTER.

SPECIFICATION forming part of Letters Patent No. 268,575, dated December 5, 1882.

Application filed June 22, 1882. (No model.)

To all whom it may concern:

Be it known that I, FREDERICK W. TOLLEY, a citizen of the United States of America, residing at Hudson, in the county of Columbia 5 and State of New York, have invented certain new and useful Improvements in Butter and Lard Cutters, of which the following is a specification, reference being had therein to the accompanying drawings.

10 This invention relates to an improvement in cutters particularly adapted for the use of grocers and provision dealers, and which will also be found very useful in families for cutting and removing butter, lard, tallow, and similar material from the jars, tubs, or kegs in which it has been packed, in clean-cut, smooth, and uniform pieces, expeditiously and without waste; and the invention consists in the peculiar construction and arrangement of 15 the parts of said cutter, as hereinafter more fully described and claimed.

In the accompanying drawings, Figure 1 represents a front elevation of a cutter constructed according to my invention; Fig. 2, 20 a side view of the same when in use; and Fig. 3, a plan view of the same, also shown in use. Fig. 4 is a front view, showing a single knife.

In the form shown in the drawings, A represents a thin horizontal blade, provided with 25 a front curved cutting-edge, a, and having two thin, narrow standing blades, B, provided with cutting-edges b b, also preferably slightly curved. These blades are inclined backward, and are set rather wider apart at top than at bottom, and have their back edges slightly 30 wider apart than the cutting-edges of the same, for the purpose of causing the blades to properly clear themselves by making the incisions wider than the blades are thick.

35 Attached to the center of the back of the horizontal blade is a shank, C, slightly curved, which may be either made separate from the blade and attached thereto by riveting, brazing, or in any other convenient manner, or it 40 may be made in one piece with the blade, if preferred, and may be round in cross-section or flattened, as desired. The shank is provided with a wooden handle, D; but the outer end of the shank may be bent to form a handle, if 45 preferred, or the shank itself may be used as 50 a handle. The handle or its equivalent should

be arranged diagonally to the horizontal blade, as shown in Fig. 2, so that the hand will not come in contact with the material being cut.

The invention is used in the manner clearly 55 shown in the drawings—viz., by inserting the cutting-edge in the butter or other article at a convenient distance from the edge of the tub or jar and forcing it toward the edge thereof, as shown in Figs. 2 and 3, and then by giving 60 a slight oscillating movement to the handle, (as indicated by the double-headed arrow in Fig. 3,) so as to bring all parts of the edge of the horizontal blade in contact with the tub or jar. A portion of the butter is severed at its 65 bottom from the mass, and a slight vertical movement given to the handle will also sever the side edges of the portion from the mass, and the cut portion can be readily lifted out with the cutter.

70 The standing blades are set slightly inclined, in order that the first piece of butter may be more easily lifted out, as the portion thus cut will be slightly narrower at bottom than at top, and for the same reason it will more readily drop out of the cutter when the latter is reversed.

75 In forming the blade I prefer to make the cutting-edge of a curve of a radius slightly smaller than the curve of the inside of the 80 tubs or jars usually employed in packing butter, although I do not wish to limit myself to this form, as a cutter having its cutting-edge straight could be usefully employed, and the same remark applies to the edges of the standing knives. These standing knives may also 85 be made vertical and parallel; but I much prefer them in the form shown, for the reasons above set forth.

I sometimes intend to make the cutter with 90 but one vertical blade, as it can be employed to good advantage in that form, as after the first cut is made but one vertical blade is actually necessary. I therefore consider a cutter having a single vertical blade as an equivalent in some cases of a cutter provided with 95 two vertical blades.

What I claim as new is—

1. In an implement adapted for cutting butter or similar material from a tub, the combination of horizontal and standing blades, and 100 a handle arranged diagonally to the horizon-

tal blade, substantially as and for the purpose specified.

2. In an implement adapted for cutting butter or similar material from a package, the combination, with a suitable handle, of vertical and horizontal blades, the horizontal blade having a convex edge and connected to the handle, substantially as and for the purpose described.

1c 3. The combination, with the horizontal blade A and a suitable handle, of two standing blades having their cutting and rear edges at different distances apart, substantially as described.

15 4. The combination, with a horizontal blade, A, and a suitable handle, of two standing blades, having their cutting-edges inclined backward away from a line perpendicular to

the plane of the horizontal blade, substantially as described.

5. The cutting implement herein described, consisting of a horizontal blade, A, having a convex edge and two standing blades, B, inclined backward from the edge of the blade A, set wider apart at the top than at bottom, and having their rear edges wider apart than their cutting-edges, the shank C, and the handle D, all constructed and arranged substantially as described, and for the purpose specified.

In testimony whereof I affix my signature in presence of two witnesses.

FREDERICK W. TOLLEY.
